HEDDLE BAR HANGER

Paul C. Consoletti, Milford, Mass., assignor to
 Draper Corporation, Hopedale, Mass., a corpora-
 tion of Maine

Application October 1, 1951, Serial No. 249,110

4 Claims. (Cl. 139—92)

1

This invention pertains to improvements in harness frames for looms, and more specifically, improvements relating to that type of harness frame in which the heddle bars are suspended upon hangers which in turn are slideable upon and are mounted for support upon auxiliary supporting rods which are carried by the harness frame rails.

It is a general object of the invention to improve harness mechanisms so that the hangers upon which the heddle bars are suspended may be so devised as to be snapped into or from position without disturbing either the heddles, the bars upon which they are carried, or the auxiliary supporting rods from which the hangers depend, and along which they are slideable as is required for assembly and for slight movement of heddles along the frame incidental to the weaving function.

It is a more specific object of the invention to devise heddle bar hangers which may quickly be snapped into or from position on the auxiliary supporting rods and which shall at the same time, be extremely simple in construction, economically manufactured and which shall also be rugged in construction and certain in operation so that they may serve for an extended period of time without attention or likelihood of failure in performing their intended function.

In more commonly used types of harness frames, the general frame structure which includes top and bottom rails either made from wood or from some other material such as one of the lighter alloy metals and end struts is supplemented by a pair of heddle bars which may be removed from the frame after releasing the ends thereof, and upon which the numerous heddles are threaded and supported. These heddles are free to move along the length of the frame, at least for a limited extent. Of course, these heddles may be removed or others added by releasing one end of the bars and sliding them to a position where the heddles may be removed from or threaded onto the bars. These bars are normally suspended or have additional support along their length as well as at the ends, which intermediate support is afforded by certain hangers, sometimes called slide hooks, these having taken various conformations and in some instances being carried upon and slideable along what are generally known as auxiliary supporting rods which in turn are carried by the top and bottom rails. It is most frequently the practice to have these rods movable lengthwise in certain eyed threaded elements which are fas-

2

tened into the wood or other material from which the rails have been made.

In all of the constructions which have been employed in practical use, the method of assembly of the bar hangers as well as of the heddles themselves has involved threading the same onto the supplemental supporting rods, although the bars themselves are carried within open ended slots or notches. As a consequence, the removal of a hanger or repositioning thereof has necessitated drawing the auxiliary supporting rods endwise until the particular hanger or hangers the position of which is to be altered have been released. Naturally this involves considerable time and effort, and in so doing, the likelihood that the heddle bars and heddles themselves may get out of control becomes fairly great. That is more probable if the heddles themselves are of the type to be hooked over the bars rather than threaded along the length thereof.

Accordingly, the improved hanger herein described and claimed is adapted to be snapped into and from position on the auxiliary supporting rod without disturbing any of the other parts and without any likelihood of mispositioning or unintended release of the heddles or other elements which are involved. While the prior art shows some hangers which may be assembled or removed while the other parts are in place, no one of them has, so far as applicant is aware, been introduced into commercial practice. According to the instant invention, hangers comprised of bent, hardened strip steel or other appropriate material are so formed and are so provided with locking slots which, however, permit the snapping of the parts into place, that the desirable results forthcoming recommend the use of this device which is adapted to serve under all circumstances and which contributes to the saving of a great deal of time as will hereinafter be apparent. In addition these improved hangers are less expensive.

The invention will be described by reference to the accompanying figures of drawing wherein:

Fig. 1 is an elevational view showing a harness frame to which the invention has been applied.

Fig. 2 is an isometric view illustrating the manner in which a hanger constructed in accordance with the invention is employed.

Fig. 3 is a schematic view showing the manner in which one of the hangers is snapped into or from position on the auxiliary supporting rod.

Fig. 4 is a detail view of one modified form of the invention, and

Fig. 5 is a detail view of another modification thereof.

Now referring to Fig. 1, the harness frame is comprised of a top rail 10, a bottom rail 11, and end struts 12 and 13. These are attached in such a manner as to provide the usual rigid framework within which is carried a plurality of heddles 14 which may take any of the well known forms common to these parts. As illustrated in Fig. 2, one type of heddle which may be employed has eyes or loops at either end which are adapted to be threaded onto the heddle bars 15 and 16, one at the top and the other at the lower part of the frame. These bars pass through the end struts 12 and 13 and project beyond a short extent having in that projecting portion of the bar an opening or drilled hole within which engages the hooked or latching end of a wire latch member 17, there being one of these at each end of each of the bars. The bars thus supported at the ends are spaced so that the heddles may slide along them, but they must necessarily be supported intermediate their ends at several points and for that purpose the heddle bar hangers generally indicated by numeral 18 are provided. These hangers are in turn suspended from top and bottom auxiliary supporting rods 19 and 20 which are threaded through eyes or openings at the ends of short threaded members or "screw eyes" 21. There are several of these for each of the rods and they are suitably spaced so as to support the rods in a relatively rigid manner.

Now referring to Fig. 2, each of the hangers 18 is of what may be termed a three-armed construction, the vertical or bar-supporting arm indicated by numeral 22 preferably being of double thickness and hooked or openly slotted adjacent its free end as shown so as to permit the entry of the bar 15 or 16 as the case may be. The open slot terminates at one side in the hooked end 23 which preferably extends part way along the width of the bar and at the other side in a shoulder 24, the dimensions of the slot or notch as compared to those of the bar being such that the bar may be snapped into position with relative ease, but once the parts have been assembled, may not rise beyond the shoulder 24 thereby to become accidentally and unintendedly released.

The other arms 25 and 26 are oppositely directed and may be considered as wings which are angularly bent away from the central arm 22. These are also bent at their ends as at 27 and 28, the said bent ends being notched as at 29 and 30, which notches are deep enough and wide enough to accommodate one of the auxiliary supporting rods 19 or 20.

In addition to the notches 29 and 30, the central or bar suspending arm 22 and also the oppositely directed arms or wings 25 and 26 are recessed or notched as illustrated at 31 and 32 so that the bar in passing through notches 29 and 30 may also pass through these centrally disposed notches 31 and 32. Once the parts have been assembled as they are in Fig. 2, the hanger may slide freely along the length of the rod 19 and also along the bar 15, the sliding movement being necessary after assembly and upon starting the loom since it is not likely that the position of the hanger will be precisely that which it should occupy once the loom has started. The free slidability lengthwise makes it possible for the heddles to assume their natural position incidental to the weaving function and, as a matter

of fact, after repairing a warp thread at which time heddles are moved endwise and the adjacent hanger or hangers also moved similarly, the parts will always return to their natural position just as soon as the loom is started and the harness mechanism moves the harness frame throughout one or more of its cycles.

In Fig. 3 the rod and a bar have been shown in position and the manner in which the parts are assembled has been schematically illustrated. The bar 15 or 16 as the case may be, is first hooked into the open slot in the arm or bar suspending portion and the opposed wing portions 25 and 26 are then applied to the auxiliary supporting rod adjacent the bar by first hooking one notch, either 29 or 30, over the rod, then springing the opposite wing portion upwardly as illustrated in the dot-and-dash lines, Fig. 3, so that the rod will enter the recesses 31 and 32 whereupon that flexed or bent wing portion may be moved to a position such that the notch therein at the down turned or bent end may be aligned with the rod. As the flexed member is released it will spring into the position shown in full lines whereupon the hanger will have been completely engaged with the bar and with the rod and may not become disengaged except by a reversal of the process which requires the positive and intended flexing of one of the wings 25 or 26 to disengage its notch 29 or 30 from the rod after which the hanger may be removed from the rod and then from the bar.

Once the parts are fully assembled they are relatively freely or loosely mounted, and although they may not become unintendedly released or disassembled, the hanger may be slid along the length of the rod and the suspended bar as required.

In the form of the invention just above described it is contemplated that the hanger be formed of two identical parts which are reversely bent and then welded or otherwise attached together thereby to form a unitary structure. According to a second mode of manufacture, a single strip of material may be employed and bent as illustrated in Fig. 4 so that there shall be no need for welding or other interconnecting steps.

A still different form has been illustrated in Fig. 5, the method of stamping out the strip and the bending thereof being substantially similar except that at the lower end of the central or bar connecting member, the bend has not been nearly so pronounced and thus the possibility of breakage at that point may be substantially eliminated. In these Figs. 4 and 5 the parts have been indicated by similar reference numerals as employed when describing the form of the invention illustrated in Fig. 2 except that these numerals have been supplemented by primes and double primes as shown.

It is obvious that the direction of pull upon the members at the lower side of the frame is opposite to that at the top, however, the principles of operation and mode of assembly are precisely the same, and in the specification and claims, the statement or terminology with reference to the bar being suspended from the auxiliary supporting rod is to be interpreted broadly enough to include the reversal of direction of forces at the lower as compared to those at the upper part of the frame. It is evident that the assembly of the hangers may be accomplished by hooking them toward the front or toward the back. There is no reason why, if desired, the recesses 31 and 32

may not be open toward the opposite side of the hanger, although it is more preferable that the open end of these recesses be directed in the same general direction or toward the same side of the unit toward which the notch into which bar 15 is received is opened.

The material from which these hangers may be made is preferably a good quality of strip steel which may be hardened so as to resist wear and also which shall have sufficient resilience or spring characteristics so that the flexing of the parts incidental to assembly may be accomplished with relative ease along with sufficient resistance against flexure so that the parts may not become detached unintendedly. The material itself may be of a rust resistant nature, or may be subjected to any of the processes adapted to render it resistant to corrosion.

The term "downturned" as applied to the ends 27 and 28 should be related to the central or bar supporting arm and, of course, is turned in the direction toward which that central arm projects, although for the top and bottom hangers the relationship in general is reversed.

The term "notches" has been used in both the specification and claims to denote that means which defines the openings 29, 30, 31 and 32. These are true notches in the sense that they are open at one end and therefore permit the assembly and disassembly of the parts as described.

While one preferred embodiment and certain modifications have been disclosed, it is to be understood that the inventive concept may be carried out in a number of ways. The invention is, therefore, not to be limited to the precise details described, but is intended to embrace all variations and modifications thereof falling within the spirit of the invention and the scope of the claims.

I claim:

1. For a loom harness frame of the type having heddle bars upon which the heddles are slidably mounted and auxiliary supporting rods from which said heddle bars are suspended, an improved heddle bar hanger which comprises a three armed member one arm of which is slotted to receive the heddle bar and the other two arms of which are resilient and provide for releasable engagement with the auxiliary bar and comprise bent outer ends, a notch in each said bent outer end engageable with the auxiliary bar, other notches centrally disposed and aligned with said notches in said bent outer ends, the open ends of the said other notches being disposed at right angles to the open ends of the notches in the 55 bent outer ends.

2. For a loom harness frame of the type having heddle bars upon which the heddles are slidably mounted and auxiliary supporting rods from which said heddle bars are suspended, an im-

proved heddle bar hanger which comprises a three armed member one arm of which is slotted to receive the heddle bar and the other two arms of which are resilient and provide for releasable engagement with the auxiliary bar and comprise bent outer ends, a notch, vertically disposed as the frame is employed, in each said bent outer end engageable with the auxiliary bar, other notches centrally disposed and aligned with said notches in said bent outer ends, the open ends of the said other notches being laterally disposed as compared to the said vertically disposed notches.

3. For a loom harness frame of the type having heddle bars upon which the heddles are slidably mounted and auxiliary supporting rods from which said heddle bars are suspended, an improved heddle bar hanger which comprises wing members disposed along and adapted to engage the said rods and a centrally disposed bar suspending portion at right angles to the wing members, said bar suspending portion having a hooked end for engagement of the bar, said wing members being resilient and having bent outer ends, a notch in each said bent outer end engageable with the auxiliary bar, other notches centrally disposed and aligned with said notches in said bent outer ends, the open ends of the said other notches being disposed at right angles to the open ends of the notches in the bent outer ends.

4. For a loom harness frame of the type having heddle bars upon which the heddles are slidably mounted and auxiliary supporting rods from which said heddle bars are suspended, an improved heddle bar hanger which comprises wing members disposed along and adapted to engage the said rods and a centrally disposed bar suspending portion at right angles to the wing members, said bar suspending portion having a hooked end for engagement of the bar, said wing members being resilient and having bent outer ends, a notch, vertically disposed as the frame is employed, in each said bent outer end engageable with the auxiliary bar, other notches centrally disposed and aligned with said notches in said bent outer ends, the open ends of the said other notches being laterally disposed as compared to the said vertically disposed notches.
